UNITED STATES PATENT OFFICE.

GEORGE T. PARR, OF ST. PAUL, MINNESOTA, ASSIGNOR TO PETER J. LAVALLE, OF ST. PAUL, MINNESOTA.

AERIAL-INSULATION-REPAIRING DEVICE.

1,269,956.

Specification of Letters Patent. Patented June 18, 1918.

Application filed May 22, 1916. Serial No. 99,175.

To all whom it may concern:

Be it known that GEORGE T. PARR, a citizen of the United States, residing in St. Paul, in the county of Ramsey and State of Minnesota, has invented a new and useful Improvement in Aerial-Insulation-Repairing Devices, of which the following is a specification.

My invention relates to an aerial wire insulating device, and particularly to a device for repairing and insulating electrical conductors while they are strung on poles and are aerially supported, without removing the same from the supports. My device is of simple construction and can be easily handled by one person while being applied or removed from the conductor or wire.

A further object is in providing a device which is small and compact and still practical in operation. With my device it is not necessary to bend the wire while being reinsulated, or while applying the device to the wire.

A further object is in a device which is practically inclosed when operating on the wire or conductor, and can also be completely closed when not in use, thereby making it easy to carry without danger of spilling the insulating liquid contained therein, and also protecting the working parts in the receptacle. My device can automatically be adjusted to different sized conductors and can be run back and forth, when locked on the same in operative position, in either direction longitudinally of the conductor.

These features and combination of parts hereinafter fully described are illustrated in the accompanying drawing, which forms part of this specification.

Figure 1 is a perspective of my device closed and as it appears when not in use.

Fig. 2 is a side elevation illustrating the device about to be placed on the conductor, or wire.

Fig. 3 is a side elevation showing my device locked in position on the conductor and ready for use.

Fig. 4 is a vertical section of Fig. 3 on the line $x-x$.

Figs. 5, 6, 7 and 8 are views of details.

Fig. 9 is a detail of an alternative form of the receptacle with a burner attached and a hand brush holder.

In the drawing, a case or receptacle A, 55 which is adapted to contain a liquid insulating compound, is formed with rounded corners and provided with a hood or cover B, which covers and protects the working parts in the receptacle A, when the device 60 is not in use.

The hood B is provided with a carrying handle C and slidably connected on one side to the base or receptacle A, by means of bars 2, which are rigidly secured to the 65 cover B near either end thereof. The free end of the bars 2 are adapted to slide in the guides 3, which are secured to the base of the receptacle and extend slightly above the top of the same. Secured to the free end 70 of each bar 2 is a spring 4, carrying an inwardly extending lug 5, on its free end, which is adapted to engage in the notches or recesses 6, formed in the base of the receptacle A in the path of the bar 2. An 75 opening 7 is formed in the bar 2, allowing free passage of the lug 5, so as to engage in the notches or recesses, 6.

When the lugs 5 are engaged in the lower notches 6, the cover B and the base of the 80 receptacle A are locked in closed position, as illustrated in Fig. 1. The springs 4 are formed with outwardly projecting ends 8, which can be readily engaged by the operator to release the lugs from the recesses. 85 Pivoted to the bars 2 are releasing triggers 9, which have free ends 10 and 11, the end 11 is adapted to be inserted between the spring 4 and the bar 2 when the lugs 5 are released or disengaged from the notches 6, 90 and thereby holding the lugs out of engagement with the notches 6, allowing the bars 2 to freely slide in the guides 3 and to open the receptacle by pulling upward on the handle C.

A connecting rod 12 is slidably secured to one side of the cover B and base A, respectively, by brackets 13 and has coil springs 14 on either end thereof. The rod 12 being adapted to limit the opening of 100

the cover from the base, and also serving to hold the hood and base together so that the bars 2 will not disengage the guides 3. The springs 14 act as cushions on the end of the 5 rod 12 and also serve to allow for a little greater opening between the base and the cover of the receptacle, when desired.

On one side of the guides 3 are formed a series of openings 16, into which stop pins 10 15 may be inserted so as to engage with the end 10, of the trigger 9, when the receptacle is being closed, and thereby automatically releases the springs 4 and allow the lugs to engage in the notches 6. The pins 15 15 may be secured to the receptacle A by means of a chain 17, of any other suitable manner to prevent accidental loss, while not in use. It is preferred to have the number of openings 16 corresponding to the 20 number of notches 6, and they are so arranged that when the pins 15 strike the ends 10 on the triggers 9, the lugs 5 are automatically released, and immediately engage in the corresponding notches 6, thereby 25 locking the hood and base in the position for which the pins were set.

Thus by marking the different openings 30 16 with numerals or other similar means, the operator can know just where to set 30 the pins 15 to give the correct gage or opening of the receptacle A when it is applied to the conductor or wire that is to be insulated. The object in doing this is to prevent the operator making a mistake in 35 setting the device for the different sized wires or conductors, and thereby preventing the machine from giving satisfactory results. By the use of the releasing pins 15, and the different openings 16, it is possible 40 for the operator to set the triggers 9 in the position illustrated in Fig. 6 and the pin 15 into the proper opening so that when he presses the device or machine together on the conductor, it will lock itself 45 automatically at the properly gaged opening between the hood and base A.

Freely journaled in the opposite ends 50 of the hood B are pulleys or sheave wheels 20, having V shaped grooves 21, which are adapted to run on the conductor to be coated and carry the device A freely along 55 on the same. The V shaped grooves 21 serve to adapt the pulleys or wheels, to the different sized conductors, at the same time 55 keep the device properly tracked.

Centrally disposed in the base of the receptacle A, is a grooved wheel 22, which also has a V shaped groove, in which are formed teeth 23, extending about the inner 60 circumference of the groove. The teeth 23 are adapted to engage the surface of the conductor D as it passes through the device and tend to rotate the wheel 22. The wheel 22 is formed with recesses 25 on its oppo-

site outer faces, in which are detachably 65 secured, in any suitable manner, annular rings 26, having secured to their inner faces, brush bristles 27, to form annular brushes 27', the ends of which meet on the longitudinal center line of the wheel 22, thereby 70 by forming a rotary brush between the rings in the wheel 22, which is adapted to sweep over the surface of the conductor and deposit or paint a coat of insulation compound upon the same. The rotary brushes 75 27' may be removed and replaced by new brushes when worn out. The lower portion of the rotary brush and wheel is adapted to be immersed in the insulating liquid, (not shown) which is carried in the receptacle 80 A. It is thus evident that as the brush is rotated by coming in contact with the conductor D, that the insulating material will be carried freely onto the conductor. The wheel 22 is freely journaled on the transverse shaft 24, which is held by the vertical supports 28, having lower squared portions 29, which are adapted to slide vertically in the guide-ways 30, the guide-ways 30 being secured to the opposite sides of the inside 85 of the receptacle A. Coil springs 31 in the guide-ways 30, just below the ends 29 of the supports 28, are adapted to keep the wheel 22 pressed firmly against the conductor D during the operation of the device. 90 Thus, should the conductor D have an enlarged portion therein, or should a connecting wire be running out to one side from the same, the springs 31 would allow the wheel 22 to be depressed without injuring 95 the device. Springs 31 also serve to keep the wheel or brush 27 in uniform contact with the conductor D. A spring catch 32 is provided on the side of the receptacle A and has engaging end 33 which is adapted 100 to penetrate the wall of the casing and bear against the support 28 on one side, so that when it is desired, the rotary brush may be locked down as illustrated in the detail shown in Fig. 8, and also shown in Fig. 2, 105 while the device is being applied to the conductor. The notch 34 in one of the supports 28 prevents accidental displacement of the rotary brush and wheel 22, should the hood be removed from the device, allowing the 110 spring catch to engage in the notch 34.

The alternative construction illustrated in Fig. 9, shows a burner L, attached to the bottom of the receptacle A, having a fuel supply tank M, and is adapted to heat the insulating liquid in the receptacle and keep it hot while applying the same to the conductor D. A shield N encircles the burner to protect it from the wind, etc., and has a series of openings 30 near the bottom of the receptacle A, which allow an egress of heat from the burner, the receptacle A being 115 preferably formed of metal or any suitable 120 125

material that will withstand heat. By applying the insulating compound hot a great advantage is obtained, as the compound will be deposited on the conductor smoother, and 5 also penetrate the old insulating material which may be left on the conductor.

A brush holder O, illustrated in Fig. 9, is adapted to hold the brush R freely inside the receptacle A. With this brush the operator can paint the conductor D around the pole, when the device is carried up to the same as it is run over the conductor.

It is obvious that my device can be used without any liquid or compound when the brush is dry and clean, as a cleaner. In using it as a cleaner, it would probably be preferred to have one device, the same as illustrated, without the burner, which would be used on the conductor just prior to using 10 the device which contains the liquid insulating compound. Thus, all of the surplus ragged surfaces of old insulating material on the conductor would be thoroughly cleaned off.

25 A cleaner in the form of a brush might also be used, and could be attached to the side of my device in such a way that it would run over the conductor before it passes through the insulating device.

30 In operation the receptacle A is partially filled with a liquid insulating material or compound, and the lugs 5 are disengaged from the notches 6. The triggers 9 are then set in position as illustrated in Fig. 6, so 35 as to hold the lugs 5 out of engagement with the notches 6; and by pulling upward on the handle C, the device is opened to the full width allowed by the connecting rod 12. In this open position, the device is placed 40 on the conductor D, as illustrated in Fig. 2. The releasing pins 15, are then placed in the openings 16, to correspond with the gage of the conductor, about to be insulated. The operator then with one hand on the hood B, 45 and the other under the base of the receptacle A, presses the two together. As this is done, the ends 10, of the triggers 9, will strike the pins 15, and automatically release the lugs 5, on each of the bars 2, thus locking 50 the insulating device in the proper operating position on the conductor, ready for use. A ring 35, is secured in the depression 36, of the base of the receptacle A, to which a snap 37 carrying a rope 38, can be secured 55 and by means of engagement with this rope, from the ground, the operator can easily pull the insulating device back and forth in either direction on the conductor D. As the receptacle slides or rolls along on the conductor, the rotary brush will paint the conductor with the insulating material, thus completely covering the surface of the same.

60 While I have illustrated one form of device, I desire to have it understood that my

invention can be carried out by other means 65 and applied to other uses, within the scope of the following claims:

Having described my invention, what I claim and desire to protect by Letters Patent is:

1. In a device for insulating electrical conductors while strung aerially, comprising, a receptacle for holding insulating compound, a cover having downwardly extending bars, 70 guide-ways secured to said receptacle adapted to receive said bars, carrying wheels freely journaled in said cover, locking means secured to said bars, adapted to automatically lock said cover and receptacle closed, or in open position, a rotary brush journaled 75 in said receptacle adapted to be held in spring contact with the conductor, and means on the side of said receptacle for holding said brush in depressed position out of engagement with the conductor while applying 80 or removing the device from the conductor.

2. In a device for insulating electrical conductors while strung aerially, comprising, a receptacle for holding insulating compound, 90 a cover adapted to close said receptacle when not in use, said cover being slidably connected to said receptacle for vertical movement, spring catches secured to said cover and adapted to engage in notches formed in said 95 receptacle, means for holding said spring catches out of engagement with said notches, means on said receptacle for releasing said spring catches when said cover and receptacle are pressed together to lock said cover 100 and receptacle in a spaced apart position or in closed position, said receptacle having freely journaled therein a rotary brush which is adapted to engage the conductor when it is passed along the same for the 105 purposes specified.

3. In a device for insulating electrical conductors while strung aerially, comprising, a receptacle for holding insulating liquid, a cover slidably secured to said receptacle for 110 vertical movement, a connecting rod slidably secured to said cover and receptacle adapted to limit the opening between said cover and receptacle, spring means secured to either end of said rod adapted to act as cushions on 115 the same when raising said cover from said receptacle, and means contained in said receptacle for receiving and coating the conductor as the same is passed through said device.

4. In a device for insulating electrical conductors while strung aerially, comprising, a receptacle for holding insulating compound, a cover for closing said receptacle, wheels journaled in said cover for carrying said receptacle on the conductor, a grooved wheel 120 slidably journaled in said receptacle, annular brush members detachably secured to said 125

grooved wheel, means on said receptacle for holding said grooved wheel and brush members out of contact with the conductor while applying said device to the same, 5 means in said grooved wheel for engaging the surface of the said conductor when said device is slidably locked on the conductor to rotate said brush members, thereby causing

said brush to carry insulating liquid from said receptacle to the surface of the conductor, said wheels in said cover and the inner surface of said grooved wheel being V shaped, so as to automatically adjust themselves to different sized conductors.

GEORGE T. PARR.
